UNITED STATES PATENT OFFICE.

CHARLES BRUDSIG, OF WINNIPEG, MANITOBA, CANADA, ASSIGNOR TO JOHN L. PENNER, OF MINNEAPOLIS, MINNESOTA.

BROOM.

1,229,027.

Specification of Letters Patent.

Patented June 5, 1917.

Application filed November 18, 1916. Serial No. 131,753.

To all whom it may concern:

Be it known that I, CHARLES BRUDSIG, of the city of Winnipeg, in the Province of Manitoba, Canada, have invented certain new and useful Improvements in Brooms, of which the following is the specification.

The invention relates to improvements in brooms particularly to an improvement directed to the broom brush and the fastening of the brush to the handle and the object of the invention is to provide a new style of brush which is made in a durable and economical manner and to provide an attachment for releasably fastening the brush to the handle, thereby allowing a worn brush to be removed readily and a new one inserted while retaining the remaining parts of the broom which are usually discarded when the brush is worn out.

With the above objects in view the invention consists essentially in a brush formed from whisps shaped to a brush shape and having their upper ends stuck together and bound, a holder attached to the handle to receive the bound ends of the whisps and means for releasably fastening the brush in the holder, the parts being arranged and constructed as hereinafter more particularly described and later pointed out in the appended claims, reference being had to the accompanying drawing in which:

Figure 1 represents a side view of a broom embodying my invention.

Fig. 2 represents an enlarged detailed side view of the brush with the upper end inserted in the elongated band of the holder.

Fig. 3 represents a vertical sectional view through the holder.

Fig. 4 a vertical sectional view centrally through the brush and holder.

Fig. 5 a perspective view of the locking rod.

In the drawing like characters of reference indicate corresponding parts in the several figures.

1 represents a broom handle of the ordinary kind to which I attach permanently a holder 2.

The holder comprises in the present instance a wooden head 3 and an elongated or flattened metallic band 4 which is fitted on to the block and is fastened to it by nails 5.

The lower edges of the band at the sides are rolled back on themselves to provide

side tubes or loops 6 and 7 for a purpose 55 later described.

The wooden block is held by a handle permanently by one of the nails 5 which passes through the block into the handle.

8 represents the broom brush which is 60 constructed in a particular way. The whisps forming the brush pass from the bottom to the top of the brush but are not as long as in the ordinary brush and the head ends of the whisps are all gathered together and 65 stuck such as by gluing to form a head shaped to snugly enter the band of the holder. The head of the brush is also bound by sewing through as indicated at 9, 10 and 11 and in this connection it is to be noted 70 that when the head of the brush is inserted in the holder with the upper end of it butted against the block the sewing at 10 is just within the lower end of the band 75 slightly above the tubes or loops 6 and 7. These loops have curved or rounded inner surfaces and when they are pressed inwardly against the head of the brush and the lower side of the row of stitching, they will have a broad bearing surface on the 80 broom corn and will not cut or break the straws when the broom is in use and, furthermore, when these loops are clamped against the brush on the underside of the stitching, it will be impossible to remove the 85 brush head from the socket until the clamping springs are pulled out of the loops.

To fasten the brush within the band of the holder I utilize a fixed rod 12 and a locking rod 13. The rod 12 is more or less 90 of a U-shape and has its ends 12^a short and inserted within the ends of the tubes 6 and 7 permanently while the rod 13 is of an elongated U-shape and is formed from spring material so that normally it takes 95 a form as best shown in Fig. 5.

This latter rod is put in place by first spreading the normally crossed ends and then inserting them within the ends of the tubes opposite the rod 12.

The spring ends of the said rod 13, in passing in, effect the in-pulling of the sides of the band in a location directly beneath the sewing 10 and by so doing effect the tight jamming of the band on the head of 105 the brush and the consequent tight holding of the brush in the holder.

I have herein before mentioned that the

whisps of my particular type of brush are not as long as the ordinary whisps and I desire now to explain that in the ordinary broom the whisps are bound directly to the handle and for this very reason have to be considerably longer than my whisps which are not bound to the handle but are fastened to it by means of the holder.

The construction of my broom brush 10 provides a considerable saving in material as the corn whisps usually used for broom manufacture are quite long enough to cut centrally of their length and form two brushes when the said brushes are made in 15 accordance with my invention. They are not, however, long enough to permit of the making of two broom brushes when cut for binding to the handle directly as is usually done.

There is always considerable loss of material when making up brushes in the ordinary way while in my case there is very 20 little loss as the length of the whisps supplied is approximately the length of two of my broom brushes.

25 What I claim as my invention is:—

1. A refillable broom comprising a handle, a block secured thereto, a band secured to said block and encircling the same to form a socket, the lower edges of the side walls 30 of said band having loops with rounded inner faces formed therein, a brush having a head fitting snugly within said socket and seated against said block, said head having a row of stitches extending across the same 35 and positioned within said socket and above said loops when the parts are assembled, and spring members for entering said loops and squeezing said inner faces inwardly beneath and against said stitches, thereby locking 40 said brush head within said socket.

2. The combination with a broom handle, of a flat wooden block secured to the handle, a flattened metallic band secured to and extending from the block and forming with the block a holder, said band having the 45 lower end thereof at the sides turned to provide side tubes, a broom brush having a solid head insertable within the holder and with the upper end thereof butting against the underside of the block and provided 50 with a row of stitching passing across the brush in a location immediately above the side tube and a withdrawable spring clamping wire insertable within the tubes and adapted when inserted to squeeze the tubes 55 inwardly toward the brush and beneath the row of stitching.

3. A refillable broom comprising a handle, a block mounted thereon, a band secured to said block and encircling the lower portion 60 thereof and projecting beyond the same to form a brush socket, the lower walls of said band having loops formed therein, a brush having a head fitting within said socket and a row of stitches extending across said 65 brush and above said loops when said brush is thrust into said socket and spring clamping members, U-shaped substantially in form, straddling each end of said band and having their ends fitting within said loops 70 for squeezing them inwardly beneath and against said row of stitching, thereby locking said brush within said socket.

Signed at Winnipeg, this 19th day of October, 1916.

CHARLES BRUDSIG.
